UNITED STATES PATENT OFFICE

HERBERT J. SCHAEFFER, OF READING, PENNSYLVANIA

DESIGN FOR A DECK OF PLAYING CARDS

Application filed March 29, 1932. Serial No. 43,320. Term of patent 14 years.

To all whom it may concern:

Be it known that I, HERBERT J. SCHAEFFER, a citizen of the United States, and a resident of Reading in the county of Berks and State of Pennsylvania, have invented the new, original, and ornamental Design for a Deck of Playing Cards, of which the following is a specification.

Reference is had to the accompanying drawings forming part thereof, wherein—

I claim:

The ornamental design for a deck of playing cards substantially as shown.

HERBERT J. SCHAEFFER.
